TRANSIT CONCRETE MIXER

Henry C. Harbers, Pasadena, and Edward D. Sharpe, South Pasadena, Calif., assignors to Cook Bros. Equipment Co., Los Angeles, Calif., a corporation of California

Application December 20, 1952, Serial No. 327,092

14 Claims. (Cl. 259—172)

This invention relates to transit concrete mixers of the type in which a mixing drum is supported on the rear end of a motor truck and driven in one direction for charging and mixing concrete therein, and in the reverse direction for discharging the concrete therefrom.

In such mixers it is highly desirable to drive the drum in either direction through a mechanical mechanism connected to the forward end of the truck engine shaft, since such mechanism not only delivers the requisite horsepower to the drum for driving it to meet all conditions of charging, mixing and discharging, but it also enables the drum to be driven whether the truck is moving or at a standstill, thereby providing the particular advantage of discharging concrete from the drum at the job either continuously or intermittently, without regard to truck movement which is of great value in curb and gutter work.

Such a mechanical drum driving mechanism would have long since gone into general use were it not for the fact that due to the remoteness of the drum in respect to the front end of the truck engine shaft, the mechanism must of necessity consist of many parts which present mechanical difficulties, and, hence, is prohibitively expensive to construct and maintain.

It is, of course, possible to employ a hydraulic mechanism in place of the mechanical mechanism and to actuate the former from the forward end of the engine shaft. However, because of the high pressures required in a hydraulic mechanism to drive the drum for all conditions of charging, mixing and discharging, such a mechanism becomes impractical due to the large fluid supply required to be carried on the truck, the large and expensive motor and pump necessary, and the detrimental temperatures to which the fluid becomes heated because of the high fluid pressures necessary to the drum's operation.

When a mechanical or hydraulic mechanism of the above described type is employed, that further important advantage is attained of effecting continuous rotation of the drum during transit of the mixer to a job. In the conventional drum driving mechanism where the power is taken off of the gear transmission, each time the clutch is disengaged and the transmission moved into neutral incident to stopping forward travel of the truck, or when changing gears for different driving speeds, the force exerted by the weight of the concrete resting on the blades at the rising side of the drum, operates to rotate the drum in the reverse direction. Thus when the transmission is again put into gear and the clutch released, sudden stresses are imposed on the transmission and the mechanism which frequently operate to strip or otherwise mutilate the gears, impose damaging stresses on the entire mechanism, and make reengagement of the gears extremely difficult. By maintaining a constant driving connection between the drum and the forward end of the engine shaft to drive the drum continuously during transit of the mixer, such reverse rotation of the drum cannot occur, and, consequently, the aforesaid disadvantages are eliminated.

2

The primary purpose of this invention is to provide in a transit concrete mixer, a drum driving means which embodies both a hydraulic mechanism driven from the forward end of the truck engine, and a mechanical mechanism driven from the transmission of the truck, with manual control means for each of the mechanisms which may be operated together to drivingly connect both mechanisms to the drum, or the control means for the hydraulic mechanisms to drivingly connect it alone to the drum, all depending upon the drum driving requirements at any particular time. Thus the driving means of this invention provides the advantages of both a hydraulic mechanism and a mechanical mechanism, and the disadvantages of neither.

It is also a purpose of this invention to provide in conjunction with the hydraulic mechanism, a mechanism for raising and lowering the discharge chute of the mixer to eliminate manual actuation thereof.

A further purpose of this invention is to provide in association with the hydraulic mechanism, an actuating mechanism for a gate to close and open the discharge end of the drum according as the latter is rotated in a charging and mixing direction, or in a discharging direction.

Only one form of transit concrete mixer will be described herein, and the novel features thereof pointed out in claims.

In the accompanying drawings:

Fig. 1 is a view showing in side elevation a transit concrete mixer having applied thereto one form of drum driving means, and gate and chute actuating means embodying this invention.

Fig. 2 is a top plan view of the mixer chassis with the drum driving means, chute actuating means, and gate actuating means applied thereto.

Fig. 3 is an enlarged fragmentary perspective view showing the interlocking means for the control levers of the invention.

Fig. 4 is an enlarged plan sectional view of the control levers and interlocking means therefor.

Fig. 5 is a perspective view showing the invention schematically as applied to those parts of the mixer necessary to its operation.

Fig. 6 is an enlarged view showing the control valve units of the invention in horizontal section.

Fig. 7 is a sectional view taken on the line 7—7 of Fig. 6.

Having specific reference to the drawings, the truck mixer shown in Figs. 1 and 2 is conventional in that the rear wheels 15 are driven from the engine 16 located at the forward end of the truck, through a clutch 17 operatively connecting the rear end of the engine shaft to a transmission 18 of the gear type selectively operable by lever 19 to drive a shaft 20 which extends rearwardly and is operatively connected to the rear wheels through a differential 21.

Supported on the rear end of the truck frame for rotation about an inclined axis, is a mixing drum 22 having an open upper rear end through which the drum is adapted to be charged with concrete, mixed or unmixed, from a hopper 23 supported on a frame 24 fixed on the truck frame. The drum 22 is provided interiorly with spiral blades 25 shown in broken lines in Fig. 1, and under rotation of the drum in one direction these blades operate to feed the concrete inwardly from the open end of the drum as it is fed thereto by the hopper 23, and also to agitate the concrete and prevent setting thereof during transit of the truck to a job. When the drum is rotated in the other direction the concrete is discharged from the rear end of the drum into a chute 26. To prevent accidental discharge of concrete from the drum during transit of the truck to a job, its rear end is partly closed

by a gate 27 which is adapted to be opened to permit concrete to be discharged from the drum.

This invention consists in the main of two driving mechanisms for the drum 22, one a hydraulic mechanism, and the other a mechanical mechanism, and both of which are actuated by the engine 16. The hydraulic mechanism comprises a rotary pump 28 driven from a front end extension 29 of the engine shaft, through a chain and sprocket connection 30. Fluid is supplied to the pump 28 by a feed line 31 connected to a fluid supply tank 32, and fluid under pressure is discharged from the pump through a pressure line 33 which extends rearwardly of the truck to a valve unit 34. As will be described later herein, the valve unit 34 is connected to a second valve unit 35, and the latter is connected to the tank 32 through a return line 36.

The valve unit 35 directionally controls the circulation of pressure fluid from the pump 28 to and from a fluid motor 37 through lines 38 and 39. The motor 37 is of the conventional rotary gear type, and one gear thereof is fixed to a shaft 40 for driving the latter. From this shaft 40 motion is transmitted to a transverse shaft 41 through suitable gearing 42, and the shaft 41, in turn, is operatively connected to a third shaft 43 through suitable gearing 44. The shaft 43 is operatively connected to the forward end of the drum 22 through a chain and sprocket connection 45. These several elements, not including the motor 37, constitute a drum rotating mechanism which is adapted to be driven either by the motor or the mechanical mechanism of this invention to be later described herein, and, hence, such rotating mechanism is common to both the hydraulic mechanism and the mechanical mechanism.

The valve unit 34 is provided for the purpose of controlling the supply of pressure fluid to a conventional ram 46 comprising a cylinder 47 and a piston 48, the fluid being delivered and returned from the cylinder at either side of the piston by pipes 49 and 50. As shown in Fig. 1, one end of the cylinder 47 is mounted on the rear end of the truck by a swivel connection 51 so that it can be moved vertically and horizontally the rod 48a of the piston 48 pivotally connected as at 52 to the chute. The chute 26 is swivelly mounted on the rear end of the truck, as indicated at 26a, so that it can be adjusted horizontally as well as vertically to discharge concrete to any point desired within the range of adjustment provided by the swivel mounting.

The valve unit 34 comprises a valve housing 53 in the longitudinal bore 53a of which is a spool valve 54 movable axially by a lever 55 to occupy a neutral position and either of two extreme positions. As best shown in Fig. 6, the housing 53 is provided with an inlet port 55a to which connects the pressure line 33 to the bore 53a. The housing 53 is also provided with two passageways 56 at one side of the bore 53a, and a third passageway 57 at the other side of the bore. At the same side of the bore, as the passageway 57 are two upwardly extending passageways 58 and 58a connected respectively to the lines 49 and 50.

The valve unit 35 likewise comprises a housing 59 in the longitudinal bore 59a of which is a spool valve 60 operable by a lever 61 to occupy a neutral position and either of two extreme positions. This housing 59 is provided with a passageway 62 which, through a port 63 is connected to the passageway 57 of the unit 34. At the other side of the bore 59a a pair of upwardly extending passageways 64 and 64a are provided and positioned upon opposite side of a horizontal passageway 65. Through a port 66 this passageway 65 is placed in communication with the return line 36. The passageways 64 and 64a lead from the bore 59a to the lines 38 and 39, respectively, in order that fluid can be supplied to the motor 37 in either direction from the pressure line 33 under the control, of course, of the valve 60, and returned to the tank 32 through the line 36.

Included in the hydraulic mechanism is a fluid means for opening and closing the gate 27, that comprises a ram 67 which, as shown in Figs. 1 and 5, has the piston rod 67a thereof operatively connected to an arm 68 pivoted as at 69 on the frame 24, and secured to the gate 27 so that according as the piston is moved upwardly or downwardly the gate will be closed or opened. Pressure fluid is supplied to and returned from the ram 67 by lines 70 and 70a connected respectively to the lines 38 and 39 so that depending upon the direction of fluid supply to the pump 37 the gate will be opened or closed, as will be more fully described hereinafter.

As will be seen in Figs. 1 and 2, the valve units 34 and 35 are situated at the rear end of the truck in order that the operator, while standing in an observing position at the rear of the truck, can, through the levers 55 and 61, manipulate the valves 54 and 60 to control the delivery of pressure fluid from the pump 28 to the motor 37 and the ram 46 particularly to effect discharge of concrete from the drum at the job, and to adjust the chute 26 vertically to discharge the concrete at any desired elevation.

As an additional actuating means for the valve 60, a second control lever 71 is situated in the cab of the truck, pivoted as at 72, and operatively connected to the lever 61 by rods 73 and 74 and a bell-crank lever 75. This lever 71 enables the driver of the truck, while seated in the cab, to operate the valve 60, while in position to operate the lever 19 and the clutch 17 to effect forward movement of the truck as and when necessary.

The mechanical drum driving mechanism of this invention comprises a conventional power take-off unit generally indicated at 76, and having the drive gears 77 thereof (see Fig. 5) operated by the driving gears of the transmission 18, and driven gears 78 splined on the forward end of the shaft 40. The gears 78 are, by a lever 79 pivoted as at 80, shiftable from a neutral position to a forward position in which the shaft 40 drives the drum 22 through the intermediate mechanism, in a direction for charging the drum with concrete and mixing thereof. The lever 70 is also movable to a reverse position in which the shaft 40 is reversely driven to drive the drum 22 in the other direction to discharge concrete therefrom.

Since the shaft 40 can be driven in either direction by the unit 76 or the motor 37, it is necessary to provide some means which will prevent the unit from being connected to the shaft to drive it in a direction opposed to the direction in which it is being driven by the motor. For this purpose a latch is provided comprising a stationary keeper 81 formed on a plate 82, and a U-shaped latch member 83 pivoted as at 84 on the lever 79 so as to be movable from the position shown in Fig. 3 to that shown in Fig. 4. In the Fig. 3 position the member 83 engages the keeper 81 to lock the lever 79 against movement in either direction from a neutral position. In the position shown in Fig. 4 the member 83 locks the levers 79 and 71 to each other so that movement of either lever effects corresponding movement of the other lever. It will, of course, be understood that both levers must be in neutral position before the latch member can be moved to the lever interlocking position shown in Fig. 4. While the levers 71 and 79 are shown in Fig. 5 as having separate pivots 72 and 80, in practice they have a common pivot in the form of a pin 85 with its ends fixed in the plate 82 and a second plate 86, as shown in Figs. 3 and 4.

The operation of the invention is as follows:

To charge the drum with concrete from a source situated above the hopper 23, it is first necessary to set the drum into rotation in a forward direction, that is, counterclockwise as when viewed in Fig. 5, so that the concrete is fed forwardly in the drum under the action of the blades 25. During this charging operation the concrete flows into the rear end of the drum at a point 75 above the gate 27, it being understood that the gate is

closed during this operation. If the concrete is pre-mixed then it is only necessary to drive the drum at a relatively low speed, and to do so the hydraulic mechanism alone provides the necessary power for the purpose.

Normally the two valves 54 and 60 occupy the neutral positions shown in Fig. 6 so that fluid from the pressure line 33 is free to circulate through the valves and their housings 53 and 59 back to the tank 32. In the neutral position of the valve 54 the passageways 58 are closed to block fluid in the ram cylinder 47. To set the motor 37 into operation for driving the drum 22 in the direction required for charging, the valve 60 is moved to an extreme position in which pressure fluid from the bore 59a can pass through that passageway 64 into the line 39, fluid from the discharge side of the motor returning to the line 36 through the line 38, passageway 64a, bore 59a, and passageway 65.

The lever 61 and 71 being interconnected as described, the valve 60 can be moved to the aforesaid extreme position by either lever, but the latch member 83 must be first swung clear of the lever 71 to the position shown in Fig. 3. In this position of the latch member the lever 79 is locked in neutral position so that it cannot be accidentally moved to set the mechanical mechanism into operation in opposition to the motor 37.

With pressure fluid circulating through the motor 37 in the direction above described such fluid is also supplied to the ram 67 and in such direction as to maintain the gate 27 in closed position.

If the drum is being charged with concrete that has not been pre-mixed, the drum must be rotated at a greater speed to effect proper mixing thereof, thus requiring greater power than can be developed by the hydraulic mechanism alone. Therefore, to drive the drum as required, the mechanical mechanism is now employed to assist the hydraulic mechanism. The mechanical mechanism can be set into operation by first restoring the lever 71 to neutral position whereupon, the latch member 83 is swung to the position shown in Fig. 4 so as to interlock the levers 71 and 79. By now moving either lever forwardly the two levers are moved together, the lever 71 moving the valve 60 to the aforescribed position for circulating pressure fluid through the motor 37 to rotate the drum in a forward direction, and the lever 79 shifting the power take-off unit 76 to drive the shaft 40 in the same direction as driven by the motor. Accordingly, mechanical and hydraulic mechanisms are coupled one to the other to drive the drum at the required speed for thorough mixing of the unmixed concrete with which the drum is being charged.

Once the drum has been charged with pre-mixed concrete or unmixed concrete and the latter thoroughly mixed in the drum, the truck is ready to travel to the job, but since during such travel it is only necessary to drive the drum at a relatively low speed so as to keep the concrete therein agitated to prevent setting thereof, the mechanical mechanism may be disconnected from the shaft 40 and only the hydraulic mechanism maintained in operation. To accomplish this the levers 71 and 79 are first restored to neutral position whereupon, the latch member 83 is swung to the position shown in Fig. 3 to lock the lever 79 in neutral position and free the lever 71 for independent operation. The lever 71 is now moved to actuate the valve 60 so as to set the motor 37 into operation to again drive the drum in a forward direction.

Once the truck reaches the job concrete can be poured from the drum 22 by driving the latter in a reverse direction. If only a low rate of discharge is required, as is the case in most instances, it can be accomplished by the hydraulic mechanism alone. To do this the lever 61 is actuated by the operator while standing at the rear end of the truck in a position to move the chute 26 to the desired horizontal position, and to also actuate the lever 55 for lowering and elevating the chute to position the

discharge end thereof at the required elevation for a particular job.

Actuation of the lever 61 is such as to move the valve 60 to the other extreme position wherein pressure fluid from the bore 59a can pass to the passageway 64a and from the latter to line 38 to drive the motor 37 in the opposite direction to that previously driven so as to drive the drum in a reverse direction and discharge concrete therefrom into the chute. It will be understood that the fluid as discharged from the motor is returned to the tank 32 through line 39, passageway 64, bore 59a, passageway 65, port 66, and line 36.

To permit concrete discharge from the drum, the gate 27, of course, has to be opened, and this is effected automatically and simultaneously with driving of the motor 37, since part of the pressure fluid flowing to the motor 37 passes into the line 70 and thence to the cylinder 47 at the top side of the piston 48.

To operate the ram 46 for adjusting the chute 26 vertically, the valve 54 is moved by the lever 55 from neutral position to one extreme position or the other, depending upon whether it is desired to raise or lower the chute. To raise the chute the valve 54 is moved to that extreme position necessary to place the passageway 58 in communication with the bore 53a so that pressure fluid from the bore will flow to the lower end of the ram cylinder 47 through the line 49. Fluid from the upper end of the cylinder 47 is returned by the line 50 to the passageway 58a and finally to the return line 36 through the valve unit 35 as will be obvious from a consideration of Fig. 6. Manifestly, movement of the valve 54 to the other extreme position effects circulation of the fluid in the opposite direction to that effected for raising the chute, and thus the ram 46 is made operable to lower the chute.

It is important to note that the construction of the valves 54 and 60, and the arrangement of ports and passageways in the housings 53 and 59 are such that irrespective of the position of the valve 54, fluid can pass to the housing 59 for operation of the motor 37 in either direction as controlled by adjustment of the valve 60.

From the foregoing operation of the hydraulic mechanism to rotate the drum 22 for concrete discharge, it will be apparent that such discharge is possible irrespective of whether the truck is moving or at a standstill, since the pump 28 is at all times driven by the engine 16. This is of great advantage in pouring concrete for curb and gutter work.

If a job requires a rapid rate of concrete pouring, naturally the rotational speed of the drum must be increased beyond that possible by the hydraulic mechanism. Therefore, it is necessary to resort to the mechanical mechanism to assist the hydraulic mechanism to that end. Accordingly, the power take-off unit 76 is now drivingly connected to the shaft 40 by first restoring the lever 71 to neutral position to discontinue operation of the motor 37 and allow interlocking of the lever with the lever 79, so that when the lever 79 is moved to reverse position to effect reverse driving of the drum, the lever 71 will likewise be moved to reverse position causing the motor 37 to be driven by the pressure fluid in the same direction as the unit 76 drives the shaft 40. This insures the two mechanisms driving the shaft 40 in the same direction, and thus prevents the two mechanisms opposing each other and mutilating the gears and other parts of the mechanisms.

Although only one form of transit concrete mixer is shown and described herein, it is to be understood that various changes and modifications of the mechanical drum driving means and the hydraulic drum driving means as well as the controls therefor, may be made herein without departing from the spirit of the invention and the spirit and scope of the appended claims.

What is claimed is:

1. In a transit concrete mixer: a truck; an engine for propelling the truck; a transmission mechanism; a drum

rotatably mounted on the truck; mechanical means connected to the transmission mechanism; hydraulic means connected to the forward end of the engine shaft; a first control means for the mechanical means selectively operable to connect the latter to the drum to drive the same in either direction; a second control means for the hydraulic means selectively operable to connect the latter to the drum to drive the same in either direction; and a means movable to one position in which it interlocks the two control means to each other for simultaneous operation, and another position in which the first control means is locked against operation and the second control means released for operation.

2. In a transit concrete mixer: a truck; an engine for propelling the truck; a transmission mechanism; a drum rotatably mounted on the truck; mechanical means connected to the transmission mechanism and including a shaft; hydraulic means connected to the shaft of said engine and including a motor; a first control means for the mechanical means selectively operable to connect the latter to the drum to drive the same in either direction; a second control means for the hydraulic means selectively operable to connect the motor to the drum to drive the same in either direction; and a latching device manually movable to one position in which it interlocks the two control means with each other for simultaneous operation to cause the mechanical means to assist the hydraulic means in driving said drum, and another position in which the first control means is locked against operation and the second control means released for operation.

3. In a transit concrete mixer: a truck; an engine for propelling the truck; a selective transmission for drivingly connecting the engine to the rear wheels of the truck; a drum rotatably mounted on the truck; drum rotating mechanism; mechanical means connected to said transmission and including a power take-off unit selectively operable to drive said mechanism in either direction; hydraulic means permanently connected to the shaft of said engine and including a motor drivingly connected to said mechanism, and a valve selectively operable to cause the motor to drive said mechanism in either direction; and means so controlling actuation of the valve and said unit that both of said means can be connected to said mechanism to drive the latter simultaneously in one direction or the other.

4. Means for driving the drum of a transit concrete mixer from the truck engine, including: a selective power take-off unit; a hydraulic pump adapted to be constantly driven by said engine; a hydraulic motor selectively driven in either direction by said pump; mechanism operatively connecting the drum to said motor and said unit; a first means controlling directional operation of said motor; a second means controlling directional operation of said unit; and a third means for so controlling operation of the first and second means that said unit and said motor can be caused to drive said mechanism simultaneously in one direction or the other, or the motor alone in either direction.

5. In a transit mixer: a truck; an engine; a drum rotatably mounted on the truck and having an open rear end; a gate for closing said end; a hydraulic system including a source of fluid, a pump connected to said source and drivingly connected to the engine, a motor operated by the pump and drivingly connected to the drum, a ram for closing and opening the gate, and a valve selectively controlling circulation of pressure fluid from the pump to the motor and return to said source in either direction, and simultaneously from the pump to the ram and return to said source in either direction, so that according as the drum is rotated in one direction or the other by the motor, the ram will be operated to close or open the gate.

6. In a transit mixer: a truck; an engine; a selective transmission for drivingly connecting the engine to the

truck; a drum rotatably mounted on the truck and having an open rear end; a gate for closing said end; a chute swivelly mounted at the rear end of the truck; a rotating mechanism for the drum; a hydraulic circuit including a source of fluid, a pump permanently driven by the engine, a motor operatively connected to said mechanism, a ram for actuating the gate, a second ram for raising and lowering the chute; a valve for directionally controlling the circulation of pressure fluid from the pump to the motor in either direction and its return to said source, and simultaneously to the gate ram in either direction and its return to said source, so that according as the drum is rotated in one direction or the other, the gate ram will be simultaneously operated to close or open the gate; and a second valve for controlling the circulation of pressure fluid from the pump to the second ram in either direction and its return to said source.

7. In a transit mixer: a truck; an engine; a selective transmission for drivingly connecting the engine to the truck; a drum rotatably mounted on the truck and having an open rear end; a gate for closing said end; a chute swivelly mounted at the rear end of the truck; a rotating mechanism for the drum; a hydraulic circuit including a source of fluid, a pump permanently driven by the engine, a motor operatively connected to said mechanism, a ram for actuating the gate, a second ram for raising and lowering the chute; a valve for directionally controlling the circulation of pressure fluid from the pump to the motor in either direction, and its return to said source, and simultaneously to the gate ram in either direction and its return to said source, so that according as the drum is rotated in one direction or the other, the gate ram will operate to close or open the gate; a second valve for controlling the circulation of pressure fluid from the pump to the second ram in either direction and its return to said source; said valves having fluid passages so arranged relatively that the second valve can be actuated to raise or lower the chute without interfering with circulation of fluid to and from the motor in either direction.

8. Means for driving the drum of a transit concrete mixer from the truck engine, including: a selective power take-off unit; a hydraulic pump adapted to be constantly driven by said engine; a hydraulic motor selectively driven in either direction by said pump; mechanism operatively connecting the drum to said motor and said unit; a first means manually operable to control directional operation of said motor; a second means manually operable to control directional operation of said unit; and a third manually operable means so controlling operation of said first and second means that said unit and said motor can be caused to simultaneously drive said mechanism in either direction, or said motor alone in either direction.

9. In a transit concrete mixer: a truck; an engine for propelling the truck; a selective transmission for drivingly connecting the engine to the rear wheels of the truck; a drum rotatably mounted on the truck; drum rotating mechanism; mechanical means connected to said transmission and including a power take-off unit selectively operable to drive said mechanism in either direction; hydraulic means permanently connected to the shaft of said engine and including a motor drivingly connected to said mechanism, and a valve movable from a neutral position to either of two extreme positions for causing the motor to drive said mechanism in either direction; a first lever for actuating the valve; a second lever movable from a neutral position to either of two extreme positions for causing said unit to drive said mechanism in either direction; and a latching device having a stationary keeper and a latch member pivoted on the second lever to occupy one position in which it interlocks the two levers for simultaneous operation to occupy the same extreme positions, and another position in which it engages the keeper to lock the second lever in neutral position, and frees the first lever for operation.

10. In a transit mixer as embodied in claim 1, wherein the drum has an open rear end; a gate for closing said end; a hydraulic ram for closing and opening the gate; and means so interconnecting the hydraulic means, said ram, and the second control means that according as the latter is operated to connect the hydraulic means to the drum to drive the same in one direction or the other the ram will be operated to open or close the gate.

11. In a transit concrete mixer: a truck; an engine for propelling the truck; a transmission; a drum rotatably mounted on the truck; a mechanism operatively connected to the drum for driving the same; hydraulic means continuously driven by the engine and selectively connectable to the mechanism for driving the latter in either direction; mechanical means connected to the transmission and selectively operable to assist the hydraulic means in driving the mechanism in either direction; and manually operable means so controlling operation of the mechanical means and the hydraulic means that the two can be caused to simultaneously drive the mechanism in one direction or the other, or the hydraulic means alone.

12. In a transit concrete mixer: a drum; a first driving means for the drum of relatively low horse power; a second driving means for the drum of relatively high horse power; a first means to operatively connect the first driving means to the drum so as to rotate the latter in either direction; a second means to operatively connect the second driving means to the drum to rotate the latter in either direction; means to connect the first and second means to each other for simultaneous operation to couple both driving means to the drum for driving thereof in the same direction; and means operable to lock the second driving means in a non-connecting position when the second driving means is in a corresponding position.

13. In a transit concrete mixer: a truck; an engine for 35

propelling the truck; a transmission mechanism; a drum rotatably mounted on the truck; mechanical means connected to the transmission mechanism; a hydraulic motor; a first control means for the mechanical means selectively operable to connect the latter to the drum to drive the same in either direction; a second control means for said motor selectively operable to connect the latter to the drum to drive the same in either direction; and means permanently connecting said motor to the engine shaft for constant driving thereby so that the drum can be driven by said motor through operation of the second control means whether the truck is in motion or at a standstill.

14. In a transit concrete mixer: a drum; a first driving means for the drum of relatively low horsepower; a second driving means for the drum of relatively high horsepower; a first means to operatively connect the first driving means to the drum so as to rotate the latter in either direction; a second means to operatively connect the second driving means to the drum to rotate the latter in either direction; and means selectively operable to connect the first and second means to each other for simultaneous operation to couple both driving means to the drum for driving thereof in one direction or the other, or by the first means alone in one direction or the other.
